UNITED STATES PATENT OFFICE.

LEWIS C. BAYLES, OF EASTON, PENNSYLVANIA, ASSIGNOR TO INGERSOLL-RAND COMPANY, OF NEW YORK, N. Y., A CORPORATION OF NEW JERSEY.

PERCUSSIVE TOOL.

1,080,881.

Specification of Letters Patent.

Patented Dec. 9, 1913.

Application filed February 3, 1912. Serial No. 675,287.

To all whom it may concern:

Be it known that I, LEWIS C. BAYLES, a citizen of the United States, and resident of Easton, in the county of Northampton and 5 State of Pennsylvania, have invented a new and useful Improvement in Percussive Tools, of which the following is a specification.

The object of my invention is to provide 10 a percussive tool having a novel form of rotation device, the operation of which is controlled by means independent of the operation of the work piston.

In the accompanying drawings, Figure 1 15 represents in longitudinal central section, a percussive tool of the piston hammer type with my invention applied thereto; Fig. 2 is a cross section taken in the plane of the line A—A of Fig. 1, and Fig. 3 is a cross 20 section taken in the plane of the line B—B of Fig. 1.

The work piston is denoted by 1 and the chamber within which it reciprocates, by 2. The rotation piston is denoted by 3 and the 25 chamber within which it reciprocates, by 4. These pistons and chambers are located within the cylinders forming in the present instance a double cylinder 5, which cylinder may be provided at its rear end with a suitable handle 6, and at its front end with a front head 7. An anvil block 8 is mounted in the cylinder 5 in position to be struck by the piston 1. A chuck 9 is rotatably mounted in the front head 7, which chuck is provided with a bore for receiving therethrough the shank of a drill steel 10, the rear end of which steel is arranged in position to be engaged by the anvil block 8. The drill steel and anvil block are shown as provided with 30 axially arranged holes for supplying the pressure fluid to the drill hole to blow the cuttings therefrom. This chuck 9 is provided with a spur gear 11, which meshes with a pinion 12, the axis of which is in 35 alignment with the rotation piston 3. This rotation piston 3 is located along the side of the work piston 1, and a step by step rotary movement is imparted to the rotation piston 3 by a rifle bar 13 with which the rotation piston has a sliding interlocked engagement, said rifle bar being arranged to be 40 clutched to and released from the cylinder by means of a ratchet device 14 of any well known or approved construction. The rotation piston 3 has a sliding interlocked en-

gagement with a pinion 12. In the present instance, this is accomplished by providing the rotation piston 3 with a front extension 15, angular in cross section, which extension is fitted to slide in the bore 16 of the pinion 12, said bore being of the same angular shape in cross section as the extension 15. Means are provided for reciprocating the rotation piston independently of the work piston, which means is herein shown as an independent valve 17 located within a valve chest 18, which valve alternately opens the motive fluid inlet chamber 21 to the passages 19, 20, leading to the opposite ends of the rotation piston chamber 4.

The main controlling valve seat 22 is provided with the usual passages 23, 24, leading to the opposite ends of the work piston chamber 2, the passage 26 leading to the fluid inlet chamber 21 and the exhaust passage 25. The main controlling valve, not shown herein, may be of any well known or approved construction.

It will be seen that a novel form of rotation for the chuck is shown herein, which rotation is controlled by means entirely independent of the control of the work piston.

While I have shown and described my invention in connection with a percussive tool of the piston hammer type, still I do not wish to have it understood that I confine my invention to such a tool, as I contemplate the use of this rotation device in connection with percussive tools of any type to which it would be applicable.

What I claim is:

1. In a percussive tool, a work piston, a rotation piston arranged along the side of the work piston and reciprocating lengthwise of the tool, means for imparting a step by step rotary movement to the rotation piston, a chuck rotated by the rotation piston and means for controlling the reciprocations of the rotation piston independently of the work piston.

2. In a percussive tool, a work piston, a rotation piston arranged along the side of the work piston and reciprocating lengthwise of the tool, means for imparting a step by step rotary movement to the rotation piston, a chuck rotated by the rotation piston and a valve for controlling the reciprocations of the rotation piston independently of the reciprocations of the work piston.

3. In a percussive tool, a work piston, a

2
chuck provided with a gear, a pinion meshing therewith, a rotation piston having a sliding interlocked engagement with said pinion, means for imparting a step by step 5 rotary movement to the rotation piston and means for controlling the reciprocations of the rotation piston independently of the work piston.

4. In a percussive tool, a work piston, a 10 chuck provided with a gear, a pinion meshing therewith, a rotation piston arranged along the side of a work piston and reciprocating lengthwise of the tool, the said rotation piston having a sliding interlocked engagement 15 with said pinion, means for imparting a step by step rotary movement to the rotation piston and means for controlling the reciprocations of the rotation piston independently of the work piston.
5. In a percussive tool, a work piston, a 20 rotation piston, their cylinders, a chuck, a pinion geared thereto, a rifle bar alternately clutched to and released from the rotation piston cylinder, said rotation piston having a sliding interlocked engagement with the rifle bar and engaging said pinion for imparting a rotary movement to the chuck and means for controlling the reciprocations of the rotation piston independently of the 25 work piston.
6. In a percussive tool, a work piston, a 30 rotation piston, their cylinders, a chuck, a pinion geared thereto, a rifle bar alternately clutched to and released from the rotation piston cylinder, said rotation piston being arranged along the side of the work piston and having a sliding interlocked engagement with the rifle bar, and engaging said pinion for imparting a rotary movement to 35

the chuck and means for controlling the reciprocations of the rotation piston independently of the work piston.

7. In a percussive tool, a work piston, a rotation piston, their cylinders, a chuck, a pinion geared thereto, a rifle bar alternately 45 clutched to and released from the rotation piston cylinder, said rotation piston having a sliding interlocked engagement with the rifle bar and engaging said pinion for imparting a rotary movement to the chuck and 50 means for controlling the reciprocations of the rotation piston independently of the work piston, said means comprising a valve, its chest and passages leading therefrom to the opposite sides of the rotation piston. 55

8. In a percussive tool, a work piston, a rotation piston, their cylinders, a chuck, a pinion geared thereto, a rifle bar alternately 60 clutched to and released from the rotation piston cylinder, said rotation piston being 65 arranged along the side of the work piston, and having a sliding interlocked engagement with the rifle bar and engaging said pinion for imparting a rotary movement to the chuck and means for controlling the reciprocations of the rotation piston independently of the work piston, said means comprising a valve, its chest and passages leading 70 therefrom to the opposite sides of said rotation piston.

In testimony, that I claim the foregoing as my invention, I have signed my name in presence of two witnesses, this first day of February 1912.

LEWIS C. BAYLES.
